Primary Examiner — Kendra Leslie Hamilton(74) *Attorney, Agent, or Firm* — ScienBiziP, P.C.(57) **CLAIM**

The ornamental design for a bottle lid, as shown and described.

DESCRIPTION

FIG. 1 is a top, front, right perspective view of a bottle lid, showing my new design in a first configuration, wherein the nozzle is stowed within the lid.

FIG. 2 is a top, rear, left perspective view thereof.

FIG. 3 is a front elevation view thereof.

FIG. 4 is a rear elevation view thereof.

FIG. 5 is a left side elevation thereof.

FIG. 6 is a right side elevation thereof.

FIG. 7 is a top plan view thereof.

FIG. 8 is a bottom plan view thereof; and,

FIG. 9 is a top, front, right perspective view of the bottle lid of FIG. 1, shown in a second configuration, wherein the nozzle is deployed.

The broken lines illustrate portions of the bottle lid that form no part of the claimed design.
